UNITED STATES PATENT OFFICE.

WILLIAM H. DUNHAM, OF HOKAH, MINNESOTA, AND JAMES WIDNEY, OF ALLEGHENY, ASSIGNORS OF PART INTEREST TO SAMUEL P. ROSS, OF PITTSBURG, PENNSYLVANIA.

IMPROVEMENT IN CAR-BRAKES.

Specification forming part of Letters Patent No. 71,591, dated December 3, 1867; reissue No. 4,465, dated July 11, 1871.

DIVISION A.

To all whom it may concern:

Be it known that we, WILLIAM H. DUNHAM and JAMES WIDNEY, the former now of Hokah, State of Minnesota, the latter of the city of Allegheny and State of Pennsylvania, have invented a certain Improvement in Car-Brakes; and having assigned a portion of our interest in the same to SAMUEL P. ROSS, of the city of Pittsburg and State of Pennsylvania aforesaid, the following is a specification:

The invention consists of a new and improved car-brake, arranged by means of levers, pulleys, rods, and chains, so that the brake-beams may be dispensed with and a compound leverage obtained for bringing the brake to bear with force upon the truck-wheels.

The accompanying drawing represents the machine and its parts. Figure 1 is a longitudinal section of a car-truck provided with our improvement. Fig. 2 is an end view of the same, and Fig. 3 is a top view of the trucks of a car with portions of the frame broken away for the purpose of showing the improvement.

The car-truck and wheels are constructed and arranged in the ordinary manner. A is the truck-frame. B B are the wheels. C C' represent iron levers, held in their proper positions by slotted hangers or supports h, made of wrought or cast-iron and bolted to the truck-frame A. 5 are bolts passing through the ends of the slotted supports or hangers h and through the levers C C', about three to five inches from their outer ends, where they are attached to the brake-heads. These bolts act as pivots, upon which the levers are allowed to turn freely. On the inner ends of the levers C are pivoted links 7, to which is at-

tached a chain, 6, which passes around a pulley, e, on the end of lever C', and is connected to the pulley o on the shaft i, on the upper end of which is secured a transverse lever, x, to which are attached the connecting-rods 3 and 4, provided with swivel-links 2. To one end of the connecting-rod 4 is secured a chain, 15, which is attached to the ordinary brake-shaft D.

When it is desired to operate the brake the hand-shaft is turned and the chain 15 wound up, which will, by means of the transverse levers x, draw forward the rod 4 and force back the rod 3 and cause the pulley o to wind up the chain 6, thus drawing the ends of the levers C C' toward each other and forcing the brake-shoes against the wheels B. The levers, after being thus operated, are held stationary by the usual appliance of a pawl and ratchet-wheel, indicated at x'. When the pawl is tripped the springs 12 cause the levers C C' to assume their original position and thereby relieve the brakes from the wheels.

We claim—

The levers C C', pivoted to the hangers or slotted supports h, and made inoperative by the springs 12, the whole constructed, arranged, and operated as described.

JAMES WIDNEY.
